[73] Assignee: Huron/St. Clair Incorporated, Taylor, Mich.

[57] CLAIM

[**] Term: 14 Years

The ornamental design for a crossbar support for an article carrier, as shown and described.

[21] Appl. No.: 384,932

DESCRIPTION

[22] Filed: Jul. 24, 1989

FIG. 1 is a top rear perspective view of a crossbar support for an article carrier on the rear deck of an automobile showing our new design;

[52] U.S. Cl. D12/157

FIG. 2 is an enlarged top plan view thereof;

[58] Field of Search D12/157; 224/309, 321, 224/324-327

FIG. 3 is an enlarged left side elevation view thereof;

[56] References Cited

FIG. 4 is an enlarged front elevation view thereof;

U.S. PATENT DOCUMENTS

FIG. 5 is an enlarged right side elevation view thereof, and,

D. 280,983 10/1985 Schinella D12/157

FIG. 6 is an enlarged rear elevation view thereof.

4,501,386 2/1985 Rasor et al. 224/326

The broken lines are for illustrative purposes only and form no part of the claimed design.

4,534,496 8/1985 Bott 224/326

The characteristic feature of our design is the curvaceous configuration of the opening in the crossbar support which configuration varies substantially in shape and size from its outside surface to its inside surface.
